UNITED STATES PATENT OFFICE.

DAVID FIRESTONE, OF HANCOCK, MICHIGAN.

CARPET CLEANER.

Application filed January 20, 1921. Serial No. 438,644.

To all whom it may concern:

Be it known that I, DAVID FIRESTONE, a citizen of the United States, residing at Hancock, in the county of Houghton and State of Michigan, have invented certain new and useful Improvements in Carpet Cleaners, of which the following is a specification.

My invention relates to improvements in carpet, rug, and the like, cleaners, by means of which the article to be cleaned is carried through the various stages of beating, dusting, washing, and steaming, etc., whereby any dust or dirt is removed therefrom with speed and efficiency. By means of the device the article may be easily introduced into or removed from the same with the minimum amount of labor.

The object of the device is to so construct the same, that not only will an efficient machine be the result, but it will have few parts, will be cheap, durable, easily constructed and operated, and the parts comprising the same be renewed or supplied with the least possible trouble.

In the drawings forming a part of this specification, and in which symbols of reference represent corresponding parts in the several views:

Figure 1 is a side elevation of the device, the dotted lines indicating the covering for the rear of the machine, roll 3 being above shaft 40 and to the right of the same;

Figure 2 is a side elevation opposite to that shown in Figure 1;

Figure 3 is a front view, with gear 32 on shaft 31 and its associated parts left out for clearness, the same being shown in Figure 4.

Figure 4 a rear view, partly in section, the dotted line indicating the covering for the device;

Figure 5 is a sectional view, showing shafts and lever for operating same, to throw the brushes into or out of operation.

Figure 6 is a side view, showing the construction of the beaters.

In the drawings, 1 represents the pulley connected to the main drive-shaft 40; 2 a transmission pulley connected to the drive-shaft by a belt 41; 3, 4, 5 and 6 are the carrier rolls over which operate belts 24 to convey the carpet or other article to be cleaned; and 7 is the dust brush. The dust brush is operated by a band 27 passing over pulleys 42, supported by frame 43; and connected to the drive-shaft 40. 8 is the scrubbing

brush, which is operated by a band 28 passing over pulleys 44, supported by frame 45; and 9 is a vessel for the cleansing liquid.

10 is a clutch for control of the beaters, the same adapted to be operated by lever 10^a, which is journaled at 46 in the main frame; and 31 is a link connecting the lever with clutch for operating the same. 47 and 48 are shafts journaled at 49 in the frame of the machine and having connected to the same worms 11, adapted to be engaged by gears 11^b. 52 is a lever having teeth engaging a segmental rack 50, by means of which the brushes may be operated to throw them into or out of operation. 51 are springs on the rods for the purpose of keeping the belts tight while that side of the machine is in operation.

When the dry cleaning brush is to be brought into use the lever 52 is turned toward the brush to be operated, thus tightening the belts on that side; and is turned in the opposite direction to control the washing brush. When the lever is at neutral, or vertical, neither brush is running. 53 are rods supporting the brushes and being supported from the main frame by links 54, pivoted at 55 to rods 53, so as to give them a swinging movement.

14 are threaded rods for raising and lowering the vessel 9, the same being journaled in the frame at 56 and in the side of the vessel at 57. They are provided with gears 58 which engage pinions 59 on a shaft 60, and said shaft is operated by a crank 61, and the vessel adjusted as desired. 12 are threaded rods having at their base gears 62 adapted to engage wheels 63 on the ends of rod 64, which is journaled in the main frame and adapted to be operated by crank 12^a, by means of which the rods 12 may be operated in the supports 65 and 66, supported at 67 to the frame, and thus the tension of the carrier belts be adjusted.

13 is a belt to be connected to the source of power, as an engine or motor. 15 is a fixed pulley connected to roller 68, from which the article to be cleaned is fed into or removed from the cleaner. 16 is a loose pulley on the above-described roller; 21 a foot lever for shifting the belt on pulleys 15 and 16 through the medium of a shaft 69 carrying fingers 70 embracing said belt. 17 is a cam shaft for operating the beaters, the same carrying cams 22. 71 is a shaft upon which are journaled a series of

- blocks 72 by staples 73; and said blocks have cut-away portions 74 within which operate base pieces 75, also journaled on shaft 71. Connected to pieces 75 are the beaters 18, which have elongated staples 76 embracing them, the purpose of the same being to control the play of the beaters. Staples 73 are fast in blocks 72. 74' are springs on blocks 72, the same being connected to shaft 71 and extending down to the base of the blocks, the beaters 18 passing beneath the same and being normally held against a rod 78, so that they are firmly held until operated upon by the cams. Rod 78 is journaled in the frame at the sides of the same in the links 79. The beaters 18 not only have a vertical movement and strike the article on the surface when the cams contact with pieces 75, but also a horizontal movement through the medium of shaft 25 carrying wheel 81 which engages gear 82 connected with the cam shaft, the other end of shaft 25 carrying a cam 83. Shaft 25 is journaled in frame 84, supported from the main frame. When cam 83 is rotated it contacts with collars 85 and 86 on shaft 71, and said shaft is reciprocated and with it the beaters. 87 are collars on shaft 71 to hold the blocks 72 in proper relation.
- 19 is the blower to create a vacuum and remove the dust as it is beaten from the article. 20 is a rack from which the article to be cleaned is fed into or removed from the machine. 88 are collars on shafts 47 and 48 the purpose of the same being to prevent the brush going too hard against the carpet. 23 is a perforated pipe from which steam may be applied to the article to be cleaned, the source of supply being connected to the end of the same. The perforated pipe forms a part of shaft 60, being journaled in the frame of the machine, as shown in Figure 1.
- 89 is a shaft upon which the blocks 72 are journaled by staples 90 located on the back of said blocks; and said shaft 89 is supported in links 79 at the sides of the machine.
- The operation of the machine will be apparent from the foregoing description. The article to be cleaned is fed from the rack onto the carrying belts which feed them into the machine as the feed rollers are operated, when it is dusted, beaten, washed, and if desired, steam applied to it. The refuse is carried from the machine by the blower or fan creating a suction. The cam shafts not only give the beaters vertical play, but they are operated horizontally by the cam. Thus the entire surface of the carpet is reached.
- Having now fully described my invention, what I claim as new, and desire to secure by Letters Patent, is:—
- 65 1. In a carpet cleaning machine, a main frame, a series of carrier rolls journaled in the same, belts on said rolls for carrying the article to be cleaned, a drive-shaft, a series of beaters, a shaft upon which the beaters are journaled, a cam shaft journaled in the frame, cams carried by the shaft and adapted to impart vertical movement to the beaters, and a cam having connection with the cam shaft and adapted to impart a reciprocating movement to the beaters.
2. In a carpet cleaning machine, a main frame, a drive shaft journaled in the same, a series of rolls also journaled in the main frame, belts on said rolls for conveying the article to be cleaned, connections between the drive shaft and feed rolls, a series of beaters, base pieces carrying said beaters, blocks having cut-away portions to receive the base pieces, a shaft journaled in the main frame and carrying the blocks and base pieces, a cam shaft journaled in the frame, cams carried by the cam shaft and adapted to contact with the base pieces to operate the beaters, springs on the blocks engaging the beaters, a rod journaled in the frame and connected with and supporting the blocks, a shaft journaled in the frame upon which the beaters rest, and a cam for giving the beaters a horizontal movement.
3. In a carpet cleaning machine, a series of beaters, a shaft carrying the same, means for giving the beaters vertical and reciprocating motion, means to throw the actuating mechanism out of operation, a series of belts to feed the article to the machine, a drive shaft having connection to the feed belts, brushes, supports carrying the brushes, belts to operate the brushes, pulleys upon which the belts operate, horizontal shafts journaled in the frame and engaging the brush supporting means, springs on the shafts to hold the brushes in operative position, worms on the shafts, a transverse journal carrying pinions engaging the worms, and a rack and lever to operate the transverse shaft to throw the brushes out of operation.
4. A carpet cleaning machine, comprising a series of beaters, a shaft carrying the same, means for giving the beaters vertical and reciprocating motion, means to throw the beating mechanism out of operation, a series of belts to feed the article to the machine, a drive shaft having connection to the feed belts, brushes to dust and wash the article, supports carrying the brushes, belts to operate the brushes, pulleys to operate the belts, horizontal shafts journaled in the frame and engaging the brush supporting means, springs on the shafts to hold the brushes in operative position, worms on the shafts, a transverse journal carrying pinions engaging the worms, a rack and lever to operate the transverse shaft to throw the brushes out of operation, a liquid vessel for

the wash brush, and means for adjusting the vessel.

5. A carpet cleaning machine, comprising beaters, a shaft upon which the beaters are journaled, a cam shaft, cams on the cam shaft, springs adapted to be operated by the cams to give the beaters vertical movement, collars on the beater shaft, a cam operating between the collars to give the beaters horizontal movement, a shaft carrying the cam, and a crown and pinion connection between the shaft and the cam shaft to operate the cam.

10 6. A carpet cleaning machine, comprising beaters, a shaft upon which the beaters are journaled, a cam shaft, cams on the shaft, a

cam connected to the cam shaft by gears and adapted to operate the beater shaft, belts to convey the carpet, rolls carrying the belts, brushes to clean the carpet, supports carrying the brushes, horizontal shafts journaled in the frame and engaging the brush supporting means, springs to hold the brushes in operative position, worms on the shafts, a transverse journal carrying pinions engaging the worms, a lever to operate the pinions, means to adjust the tension of the belt rolls, and a roller to convey the carpet to the machine.

15 In testimony whereof I affix my signature.

DAVID FIRESTONE.
